(57) **CLAIM**

The ornamental design for a inlet locking collar for hose reel as shown and described.

DESCRIPTION

FIG. 1 is a top perspective view of an inlet locking collar for a hose reel;

FIG. 2 is a bottom perspective view thereof;

FIG. 3 is a top plan view thereof;

FIG. 4 is a front elevational view thereof;

FIG. 5 is a left-side elevational view thereof;

FIG. 6 is a right-side elevational view thereof;

FIG. 7 is a bottom plan view thereof; and,

FIG. 8 is a rear elevational view thereof.

1 Claim, 3 Drawing Sheets
